(Cl. D15—1)

To all whom it may concern:

Be it known that we, Donald G. Wogomon and Henry Pederson, citizens of the United States and residents of Goshen, Elkhart County, Indiana, have invented a new, original, and ornamental Design for a Chaise Longue, of which the following is a specification, reference being had to the accompanying drawing, forming a part thereof.

In the drawing:

Figure 1 is a perspective view of a chaise longue, showing our new design; and

Figure 2 is a rear end elevation of the chaise longue.

We claim:

The ornamental design for a chaise longue, as shown.

DONALD G. WOGOMON.
HENRY PEDERSON.
